(57) **CLAIM**

The ornamental design for a utility cart, as shown and described.

DESCRIPTION

FIG. 1 is a front perspective of a utility cart of the present invention.

FIG. 2 is another front perspective view of the utility cart.

FIG. 3 is a left-side perspective view of the utility cart.

FIG. 4 is a right-side perspective view of the utility cart.

FIG. 5 is a rear perspective view of the utility cart.

FIG. 6 is a view showing the top planar of the utility cart.

FIG. 7 is a portion of top planar view of utility cart with a lid off; and,

FIG. 8 is a front perspective view of the utility cart shown open with shelves extended.

The portions shown in lighter grey and surrounded by broken lines show portions of the utility cart which form no part of the claimed design.
